UNITED STATES PATENT OFFICE.

CHARLES W. LUMMIS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

FUEL-AGITATING MECHANISM FOR GAS PRODUCERS.

Application filed March 31, 1920. Serial No. 370,130.

The present invention relates to devices employed with gas producers for agitating the fuel bed, at or below the surface thereof. The desirability of continuously breaking up the bed of fuel in a gas producer, by causing relative traversing movement between said fuel bed and a substantially horizontal member operating at a predetermined position relative to the top or surface of said bed, is well recognized. Attempts have been made to accomplish this result, with automatic levelling or agitating members, using the resistance of the top of the fuel against the member to determine the height of the latter. These prior devices work with a fair degree of uniformity only when or as long as the condition of the fuel bed remains practically constant.

In the actual operation of a gas producer, however, there is considerable variation in the condition of the fuel bed. At certain times the fuel bed is comparatively soft, possessing only a very slight resistance, and under these conditions an agitating member of the type above mentioned is certain to sink too deep below the surface of the bed of fuel. At other times the fuel bed becomes extremely hard and impenetrable, requiring considerable effort to agitate or level it, and making necessary a very greatly increased pressure, to cause a leveller or agitator of the above type to become effective. The deep penetration of a levelling or agitating member into a soft fuel bed is not only useless, but is liable to damage the fire, while conversely the failure of such a member to penetrate the relatively hard fire bed makes said member practically ineffective at a time when its operation is most needed.

The primary object of the present invention is to provide for the maintenance of a levelling or agitating member at a predetermined position relative to the top of the fuel bed, irrespective of any variation that occurs in the relative hardness or relative softness of said fuel bed. In other words, in spite of the softness of the bed and its consequent slight resistance to the member, the latter is made to sink or dig into the bed only a predetermined depth, and conversely, under the opposite conditions, with a hard bed, the member is made to dig into said bed to a similar predetermined depth. Two forms of mechanism, by which the above and

other objects are attained, are illustrated in 55 the accompanying drawings, wherein Fig. 1 is a vertical sectional view of a gas producer, the same being equipped with a levelling or agitating mechanism having the present invention embodied therein. 60

Fig. 2 is a horizontal sectional view, showing the relation of parts in the gas producer shell.

Fig. 3 is a vertical sectional view of a gas producer, the same being equipped with a 65 form of mechanism constituting a modification of the mechanism shown in Figs. 1 and 2.

Fig. 4 is an enlarged view partly in vertical section, showing the details of the mechanism that appears in Fig. 3.

Like reference characters refer to like parts in the different figures.

Referring first to Figs. 1 and 2, the gas producer shell, containing the fuel bed, is 75 indicated by the numeral 1, and the levelling or agitating member by the numeral 2. In order to obtain the necessary relative traversing movement between the fuel bed and the member 2 the shell 1 is adapted to be 80 rotated in any suitable manner, as by means of a worm 3, in engagement with a worm wheel 4 which is fixedly secured to the shell 1.

The member 2 is here shown in the form 85 of a hollow bar having a substantially radial disposition in the shell 1. Said bar is attached to the lower end of a hollow shaft or spindle 5, the latter having a flexible hose connection 6 by means of which water 90 may enter said shaft and circulate through the same and the bar 2, in order to keep the device cool. The shaft 5 passes upwardly through the stationary top or cover section 7 of the producer, said cover section 7 making the usual water seal 8 with the rotating shell 1. Near its upper end the shaft 5 passes through bearings 9, 9, provided by a bracket 10 which is carried by the cover section 7. Said shaft 5 has a spline connection 95 11 with one of said bearings, thereby preventing rotation of said shaft, but permitting its vertical movement.

The vertical movement of said shaft is secured by means of a nut 13' which is in 105 engagement with a threaded portion 12 of the shaft, said nut as here shown being formed by the hub of a worm wheel 13,

which is disposed between the bearings 9, 9. The worm wheel 13 is operatively engaged by a worm 14 that is adapted to be rotated in either direction by any suitable means; as here shown, said worm is carried by the shaft of a reversible motor 15. Rotation of the motor 15 in one direction obtains the elevation of the shaft 5 and member 2, while rotation of the motor 15 in the opposite direction lowers the shaft 5 and member 2. A mechanism for controlling the operation of the motor 15, and for causing the member 2 to respond to changes in the level of the fuel bed, irrespective of the relative hardness or softness of said bed, will now be described in detail.

The invention contemplates the elevation or lowering of the member 2 in response to the fluctuation of a member, which is adapted to ride on the surface of the fuel bed, rising and falling as said surface rises and falls, but which has no tendency whatsoever to dig into said surface or to have its position affected in any way by the relative softness or hardness of said surface, said member thus serving as an accurate indicator of the height of the fuel bed. Such a member is here shown in the form of a small light shoe or plate 16, which is secured to the lower end of a pipe 17, to which cooling water is led by means of a hose connection 18. The pipe 17 is pivotally swung from its upper end by means of a trunnion 19 that is hung in the top or cover section 7 of the producer. The pipe 17 provides on the opposite side of trunnion 19 an extension or arm 20, which is pivotally connected to a link 21, the latter being secured pivotally to a member 22 forming one part of a device that serves as a pilot or indicator, and also as a controller, said device being designated as a whole by the numeral 23. The other member 24 of said device 23 consists of a shaft or spindle 25 on the lower end of which is provided two insulated contact members 26, 26', having leads 27, 27' that connect with a source of electrical supply. The first mentioned member 22 of the device 23 is in bifurcated form, and supports opposite pairs of insulated contacts 28, 28', and 29, 29'; these last mentioned contacts are so connected, by the several leads 30, 31, 32, and 33, with the motor 15 that when the motor circuit is formed through the contacts 26, 26' and 28, 28', the motor will operate in one direction, while when said circuit is formed through the contacts 26, 26' and the contacts 29, 29', the motor will operate in the opposite direction.

The lower member 22 of the device 23 is slidable vertically in an extension of the bracket 10, while the upper member 24 of said device is slidable vertically in the lower member 22. The upper member 24 has its spindle 25 threaded for an adjustable collar 34, the latter being engaged by one arm of

a lever 35, which is pivoted at 35' on the bracket 10, and has its other arm extending past the upper end of shaft 5, in the path of a pin 36 on said shaft. Beyond its point of contact with the pin 36 the lever 35 is weighted, as shown at 37, the tendency of this weight being to support the member 24 in a position which is limited by the pin 36, the latter acting as a stop for the lever 35.

In the position of the parts shown in Fig. 1, the motor 15 is inoperative, the levelling member 2 being shown in a predetermined and selected position with respect to the fuel bed, that is, in position to penetrate slightly beneath the surface thereof. Under all conditions the shoe or plate 16 floats lightly on the surface of the fuel bed, as shown in full lines in Fig. 1. Should the level of the fuel bed rise, the shoe 16 is elevated correspondingly, drawing down the link 21 and lowering, through said link, the lower member 22 of the indicating and control device 23, with reference to the upper member 24 of said device, thus indicating to an operator or observer the change that has taken place. Adjustment of the member 2, to compensate for said change in the level of the fuel bed, is effected by imparting rotation, in any way desired, to the wheel 13, here shown as adapted to be driven by motor 15. As also here shown, this adjustment may be effected automatically by the lowering or raising, as the case may be, of member 22. Such lowering brings the contacts 29, 29' into engagement with the contacts 26, 26', of the upper member 24 of the device 23, and thereby inaugurates a rotation of the motor 15 in such a direction as to raise the member 2 a sufficient distance to compensate for the rise in the fuel bed. In consequence of this elevation of the leveller 2 and its shaft 5, the pin 36 on said shaft presses against the lever 35 and lowers the opposite end thereof, thereby allowing the upper member 24 of the device 23 to descend by gravity, thus carrying the contacts 26, 26', away from the contacts 29, 29'. Thereupon, the rotation of the motor 15 ceases, and the parts, having been restored to their initial selected relative positions, by the above described operation of the motor, continue to function normally, the member 2 having been raised the same amount as the shoe 16.

In precisely the same way, a lowering of the surface of the fuel bed is responded to instantly by the shoe 16, so as to cause an elevation of the member 22, carrying the contacts 28, 28', into engagement with the contacts 26, 26', of the upper member 24. This produces a rotation of the motor 15 in the other direction, so as to lower the shaft 5 and member 2, thereby re-establishing at once the correct position of said member 2 relative to the surface of the fuel bed. Thereupon, rotation of the motor 15 is dis-

continued, because of the ensuing elevation of member 24, the collar 34 of which is acted on by the lever 35, whose weight 37 causes it to follow the pin 36 of shaft 5.

The above described mechanism, as will be seen, affords a positive means for raising or lowering the member 2, by applying thereto the power of a prime mover, such as the motor 15. The operation of the latter, in starting, stopping and reversing is automatically controlled by the guide or shoe 16, and hence the position which the member 2 assumes always bears a predetermined relation to the position of shoe 16, and is wholly unaffected by variations in the hardness, or resistance, of the fuel bed. In other words, the member 2 is made to operate at all times with suitable penetration into the fuel bed, and it makes no difference whether the fuel bed be hard or soft, this condition will always be maintained. The degree of penetration, or in other words the vertical distance between the leveller 2 and the shoe 16 can be varied at will, simply by adjusting the collar 34 up or down on the shaft or spindle 25 of the member 24. It is to be understood, of course, that the operation of the mechanism above described is not confined in any way to the maintenance, under all conditions, of the same fuel bed penetration by the member 2; the adjustments to which the indicating and control device 23 are susceptible, as well as suitable variation in the proportions of arms 17 and 20 and the two arms of lever 35, make it possible to obtain different predetermined degrees of penetration at different levels; for instance, a slight penetration when the fuel in the producer is at a low level, and a greater penetration when said fuel is at a higher level.

Figs. 3 and 4 show a variation of the invention, as regards the transmission to the levelling member of the fluctuation of the feeler or guide shoe 16. The latter, as before, rests lightly or floats on the surface of the bed of fuel in the producer, which in the present instance is shown as of the stationary type, having a shell 38, containing the bed of fuel. The levelling or agitating member is here shown as a radial arm 39, which is secured to a vertical rotating shaft 40, the latter passing upwardly through the top of the producer and being supported in bearings 41, 41, of a bracket 42. The rotation of the shaft 40 gives the necessary relative traversing movement between member 39 and the fuel bed, and makes said member 39 effective over substantially the entire area of said fuel bed, as will be well understood.

For rotation of the shaft 40, there is provided a motor 43, or other prime mover, on the shaft 44 of which is secured a worm 45, the latter being in mesh with a worm gear 46 on a vertical shaft 47. The shaft 47 carries a pinion 48 which meshes with a gear 49

that is connected to the shaft 40 by means of a key 50 slidably engaged in an elongated spline or slot 51 cut in the side of said shaft. This construction constrains the shaft 40 and member 39 to rotate always in unison with the gear 49, but allows the shaft 40 to be moved vertically, under the influence of the shoe 16, as hereinafter set forth.

Adjacent the gear 49 on the shaft 40 is disposed a gear 52, the hub of which is threaded internally, to fit the screw threads 53 on the shaft 40. The gear 52 is in mesh with a pinion 54, that runs loosely on shaft 47. The pinion 54 is in mesh with a pinion 55 that is secured to a parallel or counter-shaft 56. In the normal operation of the mechanism, the gear 52, although loose on the shaft 40, rotates in unison therewith, and with the gear 49. By reason of its screw connection with the shaft 40, the gear 52 becomes available, when desired, to change the vertical position of the shaft 40 through the instrumentality of certain change speed gearing between the shafts 47 and 56, as hereinafter described.

A gear 57 secured to the shaft 47, runs in mesh with a smaller gear 58, normally running loose on the shaft 56. These two gears 57 and 58 constitute one of the change speed devices for differentially operating the gear 52, to change the height of the shaft 40 and member 39. The other change speed device comprises meshing gears 59 and 60, the former secured to shaft 47, and the latter normally running loose on shaft 56; these gears 59 and 60 have a different ratio from the gears 57 and 58. Between the gears 58 and 60 on the shaft 56 is a clutching mechanism 61, 61, adapted when operated to clutch one or the other of the gears 58 or 60 to the shaft 56. This clutching mechanism is normally inoperative, and remains in its neutral or inoperative position as long as the level of the fuel bed remains unchanged. The clutches 61, 61, are operated by means of a pivoted lever 62, that is connected by a link or turn buckle 63, with an operating arm 64. One end of the latter is pivotally connected to a sleeve 65, carried by the upper end of the shaft 40, and the other end of arm 64 is connected by a link 66 to the arm 20 of the guide device or feeler 16, projecting above the trunnions 19 of the latter.

In the operation of the mechanism, the member 39 rotates at a constant speed and at each revolution passes under the shoe 16. When the shoe 16 responds to a rise of the fuel bed, the consequent lowering of arm 20 draws down the link 66 and causes the lever 62 to rock in a clockwise direction, throwing in the clutch 61 which operatively connects the gear 60 to the shaft 56. This renders operative the gear train 59, 60, and causes the shaft 56 to be rotated at a slower speed than the shaft 47. This in turn through the

pinions 54 and 55, constrains the gear 52 to rotate at a slower speed than the shaft 40 and gear 49, whereby through the medium of screw thread 53, the shaft and member 39 are raised an amount corresponding to the elevation of the shoe 16, so as to restore the normal position of member 39 relative to the top of the fuel bed. As the shaft 40 is elevated, the collar 65 at the upper end thereof shifts the arm 64 and causes the latter to disengage the clutch 61, thereby discontinuing the elevation of said shaft when normal conditions have been restored.

When the fuel bed drops, the consequent depression of the shoe 16 causes the arm 20 to move upwardly, thereby pushing up the link 66 and rocking the arm 62 through the turn buckle 63 in a counterclockwise direction, and clutching the gear 58 to the shaft 56. This establishes the gear train 57, 58, which causes a rotation of the shaft 56 at a higher speed than the shaft 47, which in turn causes rotation of the gear 52 at a higher speed than the gear 49 and shaft 40, so that shaft 40 moves downwardly in the gear 52 and lowers the member 39. The lowering of the shaft causes the arm 64 to follow downwardly and thereby accomplishes the unclutching of the gear 58 at the proper moment. The turn buckle 63 gives a means of adjustment, similar to the collar 34 in the first described form, for changing the vertical distance between the shoe 16 and the member 39.

I claim:

1. In a gas producer, a fuel agitating device, mechanism operable to impart a raising or lowering movement to said device, and a member, independent of said agitating device and movable in response to changes in the level of the bed of fuel in said producer, for inaugurating the action of said raising and lowering mechanism.

2. In a gas producer, a fuel agitating device, mechanism adapted to raise and lower said device, a member independent of said agitating device and responsive to changes in the level of the fuel in said producer for procuring the action of said raising and lowering mechanism, and means for automatically discontinuing the action of said mechanism when a predetermined relation between the position of said agitating device and the level of the fuel is restored.

3. In a gas producer, a fuel agitating device, and a member independent of said device and movable in response to changes in the height of the fuel bed in said producer, and means set in operation by the movement of said member for raising and lowering said agitating device.

4. In a gas producer, a fuel agitating device, a member movable in response to changes in the level of the fuel in said producer, a normally inoperative mechanism adapted to raise and lower said agitating device, and means operatively connected to said movable member for controlling said raising and lowering mechanism.

5. In a gas producer, the combination with agitating means for the fuel bed, of a member independent of said agitating means and movable in response to changes in the level of said bed, and means for procuring the raising or lowering of said agitating means in response to the movement of said member.

6. In a gas producer, a fuel agitating device supported independently of the fuel in the producer, a member supported by said fuel and movable in response to changes in the fuel level of the producer, and power-operated means, responsive to the movements of said member, for maintaining a predetermined relation between the position of said member and the position of said agitating device.

7. In a gas producer, a fuel agitating member adapted for vertical adjustment and supported independently of the fuel in the producer, a second member supported on said fuel and whose position changes in accordance with changes in the level of said fuel, and means for adjusting said agitating member with reference to the position of said second member.

8. In a gas producer, a fuel agitating member adapted for vertical adjustment and supported independently of the fuel in the producer, a second member supported on said fuel and whose position changes in accordance with changes in the level of said fuel, means for adjusting said agitating member with reference to the position of said second member, and means exterior to the producer chamber for indicating the relative positions of said two members.

CHARLES W. LUMMIS.
